Inventor:

V. R. Holmes

VARICK R. HOLMES, OF GRAND RAPIDS, MICHIGAN.

Letters Patent No. 85,827, dated January 12, 1869.

COVER FOR KETTLES.

The Schedule referred to in these Letters Patent and making part of the same.

To all whom it may concern:

Be it known that I, VARICK R. HOLMES, of the city of Grand Rapids, county of Kent, and State of Michigan, have invented certain new and useful Improvements in Covers for Kettles; and I do hereby declare that the following is a full, clear, and exact description thereof, reference being therein had to the accompanying drawings, and to the letters of reference marked thereon, in which—

Figure I is a top view of the cover, showing one spring, the opening, and parallel wires;

Figure II is a bottom view of the cover, showing the springs, opening, and parallel wires; and

Figure III is a view of the small cover to the openings shown in Figs. I and II.

My invention consists of an ordinary tin cover for kettles, with the following changes, additions, and improvements:

To the rim of the cover, marked E, are attached three springs, equidistant from each other, by means of solder or rivets.

The springs D are made in the form represented in Figs. I and II, of thin strips of brass, or other suitable material, and are so adjusted as to extend outwardly from the rim E about one-eighth of an inch more in a large cover and less in a small one, the points of the spring turning inward, as represented.

When the cover is placed on a kettle, the springs press against its sides, and thus hold the cover firmly in its place.

On one side of the cover is an opening, F, furnished with wires, C C C, placed parallel to each other, and fastened by solder to the under side of the cover at their ends.

These wires are placed far enough apart to permit water or other like liquid to flow freely between them, and at the same time retain in the kettle any solid substance or matter that it may be desirable to retain.

For ordinary purposes, these wires should be placed about one-twelfth of an inch apart.

Wire cloth may also be used, instead of the parallel wires, with like effect, and in such case the meshes should be from one-twelfth to one-eighth of an inch in diameter.

The opening is furnished with a cover, A, made of a single piece of tin, and having a small handle.

This small cover is movable, and is held to its place by the guides B B, which overlap its edges.

The improvements in covers for kettles may be applied to covers in any of the usual forms, the form, size, and material of which they may be made, varying according to the size of the kettle, and the purpose for which they are to be used.

The form represented in the accompanying drawings I regard as being the most simple and durable.

The object and use of my invention are to afford a means of escape for surplus steam, when such escape may be desirable in cooking, without removing the cover of a kettle to afford a strainer, through which water or other liquid may be turned off from a kettle, while solid matter will be retained within it, and also to hold the cover in its place on a kettle while water or other liquid is being turned off, as aforesaid.

What I claim as new in my invention, and desire to secure by Letters Patent, is—

The kettle-cover above described, provided with springs D, grated opening F, and slide A; substantially as and for the purposes set forth.

In testimony that I claim the foregoing, I have hereunto set my hand and seal, this 11th day of July, A. D. 1868.

VARICK R. HOLMES. [L. S.]
